UNITED STATES PATENT OFFICE.

EDWARD JAMES, OF CLEVELAND, OHIO, ASSIGNOR, BY MESNE ASSIGNMENTS, TO THE YOUNGSTOWN SHEET AND TUBE COMPANY, OF YOUNGSTOWN, OHIO, A CORPORATION OF OHIO.

MANUFACTURE OF FLEXIBLE METAL TUBING.

Application filed August 5, 1911. Serial No. 642,532.

To all whom it may concern:

Be it known that I, EDWARD JAMES, a citizen of the United States, and a resident of Cleveland, county of Cuyahoga, and State of Ohio, have invented a new and useful Improvement in the Manufacture of Flexible Metal Tubing, of which the following is a specification, the principle of the invention being herein explained and the best mode in which I have contemplated applying the principle, so as to distinguish it from other inventions.

The present invention relates in general to the manufacture of flexible tubing, and has, as its principal object, the provision of means for the manufacture of flexible metal tubing of the kind that consists of two wires coiled one within the other. To the accomplishment of these and related ends, said invention, then, consists of the means herein-after fully described and particularly pointed out in the claims.

In said annexed drawings and the following description set forth in detail certain mechanism embodying the invention, such disclosed means constituting, however, but one of various mechanical forms in which the principle of the invention may be used.

In said annexed drawings:—

Figure 1 is a side elevation of a machine embodying the invention.

Figure 2 is a view partly in section and partly in elevation of a part of the machine, the parts being shown on an enlarged scale, and the section being taken on the plane indicated by line C—C of Figure 1.

Figure 3 is a detail, transverse sectional view of a slightly modified form of die detached, the section being taken on the plane indicated by line 3—3 of Figure 4, and fragments of the friction rolls being indicated.

Figure 4 is a longitudinal, horizontal section through the die taken on the plane indicated by line 4—4 of Figure 3.

Figure 5 is a vertical section taken transversely through one of the wire guides at the place of oil supply communication.

Figures 6 and 7 are views similar respectively to Figures 4 and 3 of another modified form of the die.

Referring to the drawings, the machine comprises a suitable frame 1 to which is suitably secured a die 2 which will be hereafter described in detail, a convenient mode of at-

tachment being to screw the threaded shank 55 32 of the die into the frame.

Rotatably mounted in the frame 1 are two rolls 3—5 which, by means of suitable gears not shown, may be driven by a power shaft 7. Opposite the respective rolls 3—5 60 are two co-operative rolls 4—6 which are connected to the rolls 3—5 by gearing not shown; the rolls 4—6 are carried in a frame 8 which is pivoted on an axis parallel with the power shaft 7. This frame may be 65 slightly raised or lowered on its pivotal axis by a hand-wheel 9 which thrusts a spring 33 against the frame with more or less force, as the case may be. The two sets of rolls 3—4 and 5—6 are designed to feed forwardly two wires, and to force those wires into and through the die 2, and the slight adjustability of the rolls 4—6 provides for 70 accommodating the pairs of rolls to different sized wires.

A tube, consisting for reasons of practical construction of two parts 10—11, extends from the rolls 3—4 to the die 2 and serves as a guide tube for the wire which is being forced into the die. The parts 10—11 of the 80 tube are suitably secured at one end in the die 2, while the other ends of said parts are closely fitted in between the rolls 3—4, the passage 16 through the tube being preferably of such shape in cross-section as to contact with the wire which it is guiding in several planes only. The rolls 3—3 are peripherally grooved and the tube is provided at its corresponding end with ridges fitting into 85 these grooves; the tube is thus held against lateral movement and fits into the feed rolls so closely that the passage of fluid out around the wire is prevented. At a point intermediate between their ends, the tube parts 10—11 are secured in a support 12 90 having a tube 13 for the admission of lubricant; the tube 13 may, if desired, be secured to the frame 1 and serve as a support for the guide tube. The tube 13 is connected by an opening 17 with the opening 16 in the support 12. By means of this construction 95 of the guide tube and its supports 12—13, lubricant may be forced in around the wire as it progresses towards the die, and yet the tube gives to the wire effective support along 100 its length. It will be understood that the shape of the opening 16 may be of any desired form so long as it contacts with the

wire and yet provides a space around the wire; for instance, if round wire is being used, the opening may desirably be triangular, as illustrated. A duplicate guide tube 5 and support is placed between the die and the feed rolls 5—6.

The die itself may be formed in any one of several ways, each of which will effectively coil the two wires in the desired manner.

- 10 In Figures 3 and 4 is shown a die which is formed interiorly for the part of its length with encircling corrugations 18, into which leads an opening 19 from one of the tubes 10, the corrugations being helically formed.
- 15 Between the last corrugation 18 and the outer end of the die is a cylindrical bore 20 which is formed without corrugations; into the bore 20, near its inner end, leads an opening 21 which may be either a circular 80 opening, or which may be formed by slotting the die near its end, and into the opening 21 leads one of the two tubes 10.

When the die, as shown in Figures 2 and 3, is used in the machine, a wire X is forced 25 in the feed rolls 5—6 through the opening 19 and into the first of the corrugations 18, and as the feed of the wire continues, the wire X is coiled around by the corrugations, and at the same time advances forwardly 30 in the die. Simultaneously, a wire W, heavier than the wire X, is forced in by the rolls 3—4 through the opening 21 into the bore 20, the inner wall of which is inclined to conform with the helix of the corrugations 18. As the wire W is being coiled within the bore 20, the coiled wire X is emerging from the corrugations 18 and advances within the coil of the wire W as the latter is formed. As the coiled wire X 35 advances, it threads itself, so to speak, within the coil of wire W, and the convolutions of the two wires are forced apart and the convolutions of one wire are alternated with the convolutions of the other. The coil 40 of wire X, however, remains of smaller diameter than the coil of wire W, so that it lies substantially within the latter. In this form, the two wires emerge from the die 45 as a flexible tube composed of two wires coiled one within the other but having their convolutions interposed between one another.

50 Figures 6 and 7 illustrate another form of die. This die has the helical encircling corrugations 18 as in the former die, but instead of the cylindrical bore 20, there is provided a second series of helically formed encircling corrugations 22 into which leads an opening 23 from one of the tubes 10. The corrugations 22 have a greater diameter 55 than the corrugations 18, and are furthermore more widely spaced apart than are the corrugations 18. In operating the machine with the die shown in Figures 6 and 7, the smaller wire X is coiled by the corrugations 60 18 as before, but the larger wire W is posi-

tively coiled by the corrugations 22, and because of the separation of those corrugations the convolutions of the wire W are separated during the formation of the coil. The coiled wire W within the die, therefore, 70 practically forms a thread which forces apart the convolutions of the wire X as the latter advances into the coil of wire W. As the two coils then progress together, they emerge from the die as the finished tubing. 75

80 Although the dies shown both in Figure 4 and in Figure 6, as illustrated, are designed to receive the small wire X further from the discharge end of the die than the large wire W, this arrangement may be reversed. In such case, the corrugations of Figure 4 will be of such diameter as is required for the coil of the outer or larger wire, whereas the cylindrical bore would remain as it is shown. In the die of Figure 6, the corrugations 22, of what I will call the outer series, would remain as they are shown, but the corrugations 18, of what I will call the inner series, would remain closely spaced, but would be of the same 85 diameter as are the corrugations 22.

90 The die 2, as seen in Figures 1 and 2, is substantially identical in structure and function with that seen in Figures 6 and 7, save only that a smooth portion is left at the outer end of the bore of the die, as seen in Figures 6 and 7, whereas in the die 2 of Figures 1 and 2 the corrugations 22 extend entirely to the end of the bore. 95

100 While all of the types of dies illustrated have been shown with the corrugations 18, it is apparent that that portion of those portions of the bore of any of the dies having the corrugations may be made smooth corresponding to the formation of the bore 20 of the die seen in Figure 4, and the wires may be led in either as shown or through the openings spaced angularly of the die relative to each other. It may also become desirable to push one of the wires as shown by means of feed rolls and to pull the other wire by means of its frictional contact with the wire being pushed. 105

110 In order to reduce friction and facilitate ease and speed of operation, the die, whether of the form shown in Figure 1 or Figure 4, or Figure 6, or otherwise, is provided with openings 26 which are longitudinal notches or open-ended slots, as best seen in Figures 3 and 4, proportioned to receive the peripheral portions of friction rolls 27 and 28. The rolls 27 and 28 are preferably spaced, as shown in Figure 1, the upper roll, 28, being mounted in a frame 29, which 115 frame is mounted to oscillate on a shaft 30 and may be adjusted by the hand-wheel 31 arranged to thrust a spring 34 against the free end portion of the frame 29 with variable force, according to the friction required. 120 The adjustability of roll 28 also allows the 125 130

machine to be better accommodated to wire of different sizes. The several rolls 27-28 are geared to rotate synchronously by intermeshing gears seen in dotted lines in Figure 5 1 and driven from a source of power not shown.

In the operation of the machine, the wires W and X are forced by means of their respective feed rolls into the die 2 as above 10 explained, and the rolls 27-28, extending into the openings 26 of the die, form rolling surfaces for the wires as they are being coiled. Hence, the friction caused by forcing the wires through the die is greatly reduced. Moreover, the rolls 27-28 also exert a pulling force on the wires and thus 15 further assist the feed rolls which are forcing the wires through the die.

The wires W and X have been illustrated 20 and considered as circular in cross section, but they may be of any desired form. It may be desirable to use a large wire W circular in cross section, and to use a smaller wire X triangular in cross section. The 25 present invention is not limited to the manufacture of tubing utilizing circular wires only, but if the shape of the wires is to be different, the die may be slightly changed to conform to the shape of the wire. The main 30 features of construction of the die, however, will remain as before.

Neither is the present invention limited to the use of rolls for forcing the wires into the die, but any other suitable means may be 35 used, it being only necessary that such means be sufficient to force the wires into the die.

Other modes of applying the principle of my invention may be employed instead of the one explained, change being made as regards the mechanism herein disclosed, provided the means stated by any of the following 40 claims or the equivalent of such stated means be employed.

I therefore particularly point out and distinctly claim as my invention:—

1. In a machine of the class described, the combination of a die provided internally for part of its length with encircling corrugations, said die having a plurality of longitudinally extending openings; means for forcing two wires into said die, one of the wires being forced into said corrugations; and means disposed opposite the longitudinal openings in said die for aiding movement of the wires through said die.

2. In a machine of the class described, the combination of a die provided internally for part of its length with encircling corrugations, said die having a plurality of longitudinally extending openings; means for forcing two wires into said die, one of the wires being forced into said corrugations; and a plurality of rolls disposed opposite the respective longitudinal openings in said die.

3. In a machine of the class described, the combination of a die provided internally for at least part of its length with encircling corrugations, said die having a plurality of longitudinally extending openings; means for forcing two wires into said die, one of the wires being forced into said corrugations and the other wire being forced into the remainder of the die; and means disposed opposite to the longitudinal openings in the die for aiding movement of the wires through said die.

4. A wire coiling head or die, comprising a body portion provided with a bore comprising a spirally grooved section and with recesses which open laterally into said spirally grooved section of said bore, and anti-friction rollers rotatably mounted in said recesses, substantially as described.

5. A wire coiling head or die, comprising a body portion provided with a bore comprising a spirally grooved section and with recesses which open laterally into said spirally grooved section of said bore, and anti-friction rollers rotatably mounted in said recesses, said anti-friction rollers comprising a roller supported so as to be adjustable towards and from the axis of the bore in said head, substantially as described.

6. A wire coiling head or die, comprising a body portion provided with a bore comprising a spirally grooved section and with recesses which open laterally into said spirally grooved section of said bore, and anti-friction rollers rotatably mounted in said recesses, the last of said rollers being adjustable towards and from the axis of said bore, substantially as described.

7. In a machine of the class described, the combination of a die provided internally for part of its length with encircling corrugations, said die having a plurality of openings, means for forcing two wires into said die, one of the wires being forced into said corrugations, and means disposed opposite the openings in said die for aiding movement of the wires through said die.

8. In a machine of the class described, the combination of a die provided internally for part of its length with encircling corrugations, said die having a plurality of openings, means for forcing two wires into said die, one of the wires being forced into said corrugations, and a plurality of rolls disposed opposite the respective openings in said die.

9. An apparatus for forming flexible tubing having two wire coils of different diameters, comprising a coiling die having two coil forming walls of different diameters, there being an outlet for the formed tube leading from the wall of larger diameter, and means for forcing two wires through the die to continuously form the convolutes of the coils, the forming walls being of such di-

ameters that the convolutes of the inner coil will lie between the convolutes of the outer coil, the convolutes of the inner coil exerting an expanding force in a radial direction 5 on the convolutes of the outer coil while the convolutes of the outer coil exert a radial contracting force on the inner coil, while at the same time the convolutes of each coil are under tension tending to compress the convolutes of the other coil between its convolutes in a direction along the axis of the coils.

10. An apparatus for forming flexible tubing, comprising a die having a cylindrical opening therein, there being a laterally extending wire feed opening communicating with the interior of the die, means for forcing wire in a continuous manner through said feed opening into the die, the wall of 15 the cylindrical opening in the die being arranged to coil the wire, said die having a second cylindrical coil forming wall of

larger diameter than the first forming wall in advance of the first wall, there being a second wire feed opening in advance of the first feed opening communicating with the die in advance of the first forming wall of the die, and means for forcing wire in a continuous manner into the last feed opening, the diameters of the two coil forming walls 20 of the die being so proportioned relative to each other and the wires for forming the coils, as to cause the forming wall of larger diameter to press the convolutes of the outer coil between the convolutes of the inner coil 25 and thereby spread the convolutes of the inner coil of the tube during the formation thereof.

Signed by me this 18th day of July, 1911.

EDWARD JAMES.

ANNA L. GILL.

Certificate of Correction.

It is hereby certified that in Letters Patent No. 1,466,999, granted September 4, 1923, upon the application of Edward James, of Cleveland, Ohio, for an improvement in "The Manufacture of Flexible Metal Tubing," an error appears in the printed specification requiring correction as follows: Page 2, line 25, after the word "in" insert the word *by*; and that the said Letters Patent should be read with this correction therein that the same may conform to the record of the case in the Patent Office.

Signed and sealed this 9th day of October, A. D., 1923.

[SEAL.]

WM. A. KINNAN,
Acting Commissioner of Patents.
